FRANK FOLEY INVENTOR

BY G. H. Duthie

ATTORNEY.

UNITED STATES PATENT OFFICE.

FRANK FOLEY, OF CLARKSBURG, WEST VIRGINIA.

AUTOMATIC SHADE-DIMMED HEADLIGHT.

Application filed May 15, 1924. Serial No. 713,508.

To all whom it may concern:

Be it known that I, FRANK FOLEY, a citizen of the United States, residing in Clarksburg, in the county of Harrison and State of West Virginia, have invented certain new and useful Improvements in an Automatic Shade-Dimmed Headlight, of which the following is a full specification.

This invention comprehends certain new and useful improvements in automobile headlights.

The main object of this invention is the construction of a headlight equipped with a tilting reflector, having a lamp shade, pivotally attached within the reflector, and, when desirable adapted to cover the upper half of the light bulb, when the reflector is in the tilted position,—and electric means for tilting the reflector and raising and lowering the lamp dimming shade.

With the foregoing and other objects in view, as will more fully appear as the description proceeds, it will be observed that my invention consists of a headlight of new and novel construction, with interior combination of mechanical parts, as will herein-after be fully described, illustrated and claimed; but it is to be distinctly understood that several changes may be made in the proportions and construction of my headlight devices, without departing from the spirit and intent thereof.

I attain these objects by means of the construction and mechanism illustrated in the accompanying drawings, in which:

Figure 1 represents a vertical section of my barrel-shaped headlight showing the general position of the reflector, the raised lamp shade and operating devices within the headlight case.

Figure 2 represents the face or front of my concave reflector, showing the lamp dimming shade 6, pivotally attached within the reflector, above the lamp socket.

Figure 3 represents the plan view of the lamp dimming shade.

Figure 4 represents a side elevation of the lamp dimming shade.

Figure 5 represents a side elevation of the electric magnet.

Figure 6 represents the end elevation of said electric magnet.

Figure 7 represents a vertical section of the guide combination member and connection.

Figure 8 represents an end elevation of

the guide member, with the sliding attachments removed.

Figure 9 represents a right-angled connection member.

Figure 10 represents a side elevation of the magnet shifting lever.

Figure 11 represents the edge elevation of said magnet shifting lever.

Figure 12 represents a side elevation of the pivoted rod connections, between the guide combination members and the headlight reflector.

Figure 13 represents the edge elevation of said pivoted rod connections.

Figure 14 represents the spring locking device, removed from the guide member.

Referring to the drawings, similar numerals refer to similar parts, throughout the several views.

Numeral 1 designates the barrel shaped headlight case. Numeral 2 designates the ring flange attached to the face of the headlight. Numeral 3 the glass lens. Numeral 4 the headlight reflector. 5 the electric light bulb. 6 designates the shifting, lamp dimming shade. 7 designates the guide combination member, attached to the lower part of the headlight case. 7' the upper arm connection—a part of the guide member. 8 the sliding rod member. 9 the locking pin, adapted to engage the notches 9', in the sliding rod member. 10 designates the compression spring. 11 the rivet upon which the compression spring rests. 12 a hinge bracket, rigidly attached to the lower part of the headlight case. 13, 14 and 15 designate the three shifting rod connections, pivotally attached to the sliding rod member 8, and the reflector lug, 16, also the hinge connection, 12. 17 the right-angled connection member. 18 a connecting rod pivotally attached to the upper arm of the right-angled connection member 17, the lower end of said connecting rod being pivotally attached to one side of lug 16, on the back of the reflector. 19 a connecting rod, the lower end of which is pivotally attached to the lower arm of the right-angled connection member, the upper end of said connecting rod being pivotally attached to the lower end of the dimming shade lever, 20, which is rigidly attached to the pivot portion of the dimmer shade, and extending through and to the back of the reflector. 21 designates the pivot connection of the shifting lamp shade to the reflector. 22 designates the electric magnet frame, rig-

idly attached to the lower part of the headlight case. 23 a hinge bracket rigidly attached at the center and lower portions of the magnet frame. 24 designates the swinging magnet lever, the lower end of which is pivotally attached to the hinge bracket 23, and the upper end of said swinging magnet lever is pivotally connected to the short connecting rod 14'. The other end of said rod 19 connection is pivotally attached to the sliding rod member, 8. 25 and 25' designate the electric magnet spools rigidly attached to the upper ends of the magnet frame. 26 designates the pivot hinge connection, attached to the upper flange of the reflector, and the upper part of the headlight case, as shown in Figure 1. 27 designates the electric wire connection extending from the magnet spool 25. 28 the wire connection 20 from the magnet spool 25'. 29 the wire connection from the lamp bulb 5, all of which wire connections are fully illustrated by dotted lines—see Figure 1. All of said wires are connected to push buttons.

25 In the operation of my improved headlight, it will be observed that my headlight case is of the barrel type. The reflector is pivotally attached to the upper portion of the case by means of pivot hinge, 26, 30 which permits the reflector to swing or or tilt backward and forward in the case. The reflector is equipped with the usual electric light bulb.

35 It will be observed further that, at a suitable distance above the electric light bulb a slot extends through the reflector; that the swinging dimming shade 6, is pivotally attached by means of pivot connection 21, within the slot and upon the back of the 40 reflector. When the reflector is in the usual position, the dimming shade 6, is raised toward and against the upper surface of the reflector, as shown in Figures 1 and 2.

45 It will be observed further that when, by means of the electric magnet and connections, the reflector 4 is drawn backward to the tilted position, shown by the dotted line 4', the lamp bulb is also raised and 50 drawn backward as shown by the lamp dotted line, see Figure 1. Also, when the reflector and lamp bulb are tilted backward, the swinging dimming shade 6, changes its position, and is lowered, by the 55 same means, to the position where it covers and shades the upper half of the electric lamp bulb.

60 It will be observed still further that, in the tilting of the reflector 4, and the raising and lowering of the swinging dimming shade 6, I employ an electric magnet, which is connected to the automobile battery, and is operated by a switch or push buttons, convenient to the operator.

65 It will be observed further that by means

of the connections heretofore described, when the magnet lever 24 is in the position as shown in Figure 1, the lamp reflector is rigidly held in the usual position, and the dimming shade 6, will be raised against 70 the upper portion of the reflector, as shown in Figure 1. When the magnet lever 24 changes its position, as shown by the dotted line, and rests against the magnet 75 spool 25, the reflector will be tilted backward, as shown by the dotted lines, and the dimming shade will swing downward, to the position where it will cover and shade the upper half of the lamp bulb.

It will be observed still further that, 80 when the magnet lever 24 rests against the left hand magnet spool 25, all the lever connections change their position, as shown by the levers' dotted line positions, and when so changed, and the reflector tilted, 85 the upper portion of the lamp bulb is perfectly shaded, without dimming or reducing the candle power of the lamp; and the full lamp power sheds its light upon the road immediately and for a reasonable 90 distance in front of, the automobile, upon which the lamps are mounted. At the same time the glare and bright lamp lights, 95 are entirely shaded for the benefit and protection of the automobile's operator, or persons approaching from the opposite direction.

Having fully described my improved automobile headlight, what I claim as new and desire to secure by Letters Patent, is:—

1. An automatic, shade-dimmed headlight, of the character described, comprising a tilting reflector, attached by a hinge, to the upper portion of the headlight case, and equipped with an electric lamp at the center of said reflector; a pivoted, concave lamp shade, the entire surface of which is adapted to closely fit and rest against, the inner, upper surface of the said reflector, and adapted, when lowered, to shade the upper half of the electric lamp; and combination electric means for tilting the said reflector backward and forward upon its hinge, and automatically raising and lowering the lamp shade, as described and for the purpose set forth.

2. The combination within a headlight case, consisting of a tilting reflector, having an electric lamp in the center thereof; a swinging lamp shade, pivotally attached to the said reflector and adapted to cover and shade the upper half of said lamp; an electric magnet, rigidly attached to the rear lower portion of said lamp case; a guide combination member, rigidly attached to the lower portion of the lamp case, immediately in front of the electric magnet, having a sliding rod member, slidably attached to and within the horizontal guide portion of the combination

member; a locking pin within the guide member, adapted to engage notches in the sliding rod member; a short rod connection pivotally connected at one end to the sliding rod member, the other end pivotally connected to the swinging magnet lever; a swinging rod lever pivotally attached to the lower portion of the headlight case, between the sliding rod member and the reflector; a short rod connection having one end pivotally engaging the front end of the sliding rod member, and the other end pivotally attached to the side and upper end of the swinging lever; a rod connection one end pivotally attached to the upper end and side of the swinging lever, the other end of said rod pivotally attached to the lug of the tilting reflector; a right-angled lever, pivotally attached to the upper, curved arm of the guide member; a rod connection, the

upper end of which is pivotally attached to the upper arm of the right-angled lever, the lower end of said rod being pivotally connected to the reflector lug; a still further rod connection, the lower end of which is pivotally attached to the lower arm of the right-angled lever, the upper end of said rod being pivotally connected to the lower end of the swinging lamp shade lever,—and electric means for automatically operating the electric magnet and the connections therefrom, to the reflector and the swinging lamp shade, all substantially as described and for the purpose set forth. 25

In testimony whereof I affix my signature, in the presence of two witnesses. 30

FRANK FOLEY.

Witnesses:

HAZEL FRETWELL,
G. H. DUTHIE.
